PROPELLING AND STEERING APPARATUS FOR VESSELS

Filed Feb. 12, 1924

2 Sheets-Sheet 2

UNITED STATES PATENT OFFICE.

LOUIS ZWIESLER, OF KANSAS CITY, MISSOURI.

PROPELLED AND STEERING APPARATUS FOR VESSELS.

Application filed February 12, 1924. Serial No. 692,330.

To all whom it may concern:

Be it known that I, LOUIS ZWIESLER, a citizen of the United States, residing at Kansas City, in the county of Jackson and 5 State of Missouri, have invented certain new and useful Improvements in Propelling and Steering Apparatus for Vessels, of which the following is a specification.

My invention relates to improvements in 10 propelling and steering mechanisms for vessels and one object is to provide novel propelling mechanisms whereby a vessel may be forced forwardly or backwardly through the water, or laterally to either side, or turned 15 within its length as if upon a vertical axis, to the end that said vessel may be maneuvered with greater ease than heretofore when on the high seas, or approaching a dock.

Another object is to provide a novel steering 20 mechanism embodying a balanced rudder which may be controlled with less effort than rudders of the usual type.

Other objects will hereinafter appear, and in order that the invention may be fully 25 understood reference will now be had to the accompanying drawings, in which:

Fig. 1 is a broken longitudinal central section of a vessel embodying the improvements.

Fig. 2 is a broken front elevation partly in section of the vessel.

Fig. 3 is an irregular cross section of the vessel on line III—III of Fig. 1.

Fig. 4 is a broken plan view of part of 35 the shafting and clutch mechanism.

Fig. 5 is a broken horizontal section on line V of Fig. 1, showing the rudder and associate parts.

Referring now in detail to the various 40 parts, 2 designates the hull of the vessel which has lower and upper compartments 4 and 6, respectively.

The lower compartment 4 is provided with fore and aft cylindrical housings 8 and 10, 45 respectively, which, in the present instance are arranged in groups of three, those in the rear group being in axial alinement with those in the forward group. The adjacent ends of the housings 8 and 10 are spaced 50 apart to leave an engine or motor room 12 containing in the present instance, three motors 14 which are, preferably, of the synchronous and reversible type.

The forward ends of the housings 8 have 55 inlets 16 at the bow of the vessel and outlets 18 at their rear ends for the intake and dis-

charge of water. Drift-wood and other débris is prevented from entering the inlets 16 by guards 20 fixed to the front of the hull 2. The outlets 18 are equipped with 60 guards 21, to prevent the entrance of drift-wood and other débris when rotation of the propellers hereinafter described is reversed to back the vessel.

Each housing 8 is equipped with an elongated screw propeller 22 having a series of convolutions 24 extending around a central shaft 26 journaled in bearings 28 and 29. The bearings 29 are provided with stuffing boxes 30 to prevent water from leaking into 65 the motor room 12 from around the shaft 26. The end of each shaft 26 which extends into the motor room 12 is provided with a 70 slideable clutch member 32 controlled by a lever 34 whereby it may be shifted into and out of engagement with a companion clutch member 36 fixedly mounted upon the motor shaft 38.

Each rear housing 10 has an inlet 40 at 75 the bottom of the hull 2 and an outlet 42 at the stern of said hull, and like each housing 8 has an elongated screw propeller 44 similar to the screw propellers 22. Débris is prevented from entering the inlet 40 by guards 45. Each propeller 44 has a centrally disposed shaft 46, journaled in bearings 48 and 50, the former of which has a stuffing box 52 to prevent water from leaking 80 into the motor room 12 from around the shaft 46. Each shaft 46 is provided at its forward end with a clutch member 54 slidably mounted thereon and controlled by a lever 56 whereby it may be shifted into and out of engagement with a companion clutch member 58 fixed upon the motor shaft 38. 85

The upper compartment 6 is provided with a plurality of oppositely disposed cylindrical housings 60 and 62, four being employed in the present instance. The 90 housings 60 are arranged in axial alinement with the housings 62 and have ports 64 at one side of the hull 2 and ports 68 at the bottom of said hull, as best shown by Fig. 3. Drift-wood and other débris is prevented 95 from entering the ports 64 and 68 by guards 72 and 73, respectively, secured to the hull 2. The housings 62 have ports 66 at the opposite side of the hull 2 and ports 70 at the bottom of said hull. Guards 74 and 75, are placed over the ports 66 and 70, respectively, 100 to exclude débris.

The housings 60 and 62 like the housings

8 and 10 are below the water line and are equipped with propellers 76 and 78, respectively, of the same type as the other propellers hereinbefore described. Each oppositely-disposed set of propellers 76 and 78 are mounted upon a common shaft 80 journaled in bearings 82 and 84, the latter having stuffing-boxes 86 to prevent water from leaking into the compartment 6 from around said shaft 80. The shafts 80 are provided intermediate their ends with slidables sleeves 88 equipped at their ends with bevel gears 90 and 92, which may be adjusted to neutral position or caused to alternately engage bevel gears 94 when the sleeves 88 are shifted through the intermediacy of levers 96. The bevel gears 94 are fixedly mounted upon the ends of a drive shaft 98 driven by a suitable motor 99.

With the propelling mechanism arranged as shown and described it is apparent that when all of the propellers 22 and 44 are in operation the vessel will be forced through the water at maximum speed. It is also apparent that said propellers will operate under the most favorable conditions as they are not exposed to the action of the waves which subject the ordinary exposed propellers to all kinds of stresses. The operation of the propellers 22 and 44 will also be attended with the greatest efficiency owing to their large number of convolutions acting on the water passing through the housings 8 and 10, respectively. Furthermore, should one of the propellers 22 or 44 get out of order it can be readily thrown out of gear with its respective motor 14 through the intermediacy of the intervening clutch mechanism, so that the vessel may proceed on her course.

The propellers 76 and 78 are only used in turning the vessel or in docking the same. By driving the forward shaft 80 in one direction and the rear shaft 80 in a reverse direction, which may be accomplished by proper manipulation of the levers 96, the vessel may be turned as upon a vertical axis; and by driving said shafts 80 in the same direction the vessel will be propelled laterally and may be docked in a space between two other vessels, which a vessel guided by its rudder in the usual manner could not enter or leave.

Referring now to the steering mechanism, each of the rear housings 10 is equipped with a rudder 100 mounted upon a vertical post 102, which may be turned by any suitable means such as a handle 104. The post

102 extends through the rudder 100 at a point about midway between the ends of the same, so that the water will act equally, or substantially so, upon the forward and rear ends 102 and 104, respectively, and thus render said rudder 100 easy to control. The forward portions of the rudders 100 are reduced slightly to fit within the rear portions of the respective housings 10, as shown more clearly by Fig. 1.

The rudders 100 are used in steering the vessel when on the high seas, at which time the propellers 76 and 78 are inactive unless it should become necessary to make a sharp turn to avoid another vessel or other object.

From the foregoing description it is apparent that I have provided propelling and steering mechanisms embodying the advantages above pointed out, and while I have shown and described the preferred construction, combination and arrangement of parts I reserve the right to make such changes as properly fall within the spirit and scope of the invention as claimed.

Having thus described my invention, what I claim and desire to secure by Letters Patent, is:

1. In a propelling apparatus for vessels a group of parallel housings in the forward portion of the hull and having ports at their ends, a group of housings in the rear portion of the hull having ports at their respective ends and arranged in alinement with the forward group, elongated screw propellers arranged within the respective housings, driving mechanism whereby all of the propellers may be simultaneously driven, and means whereby any of the propellers may be thrown out of gear while the others continue to operate.

2. In a propelling and steering apparatus for vessels a housing arranged in the hull and having ports at its ends, an elongated screw propeller arranged within said housing and having a plurality of convolutions, a driven shaft upon which said propeller is fixedly mounted, a balanced rudder having its forward end reduced and extending into the rear end of the housing, and a steering post extending through the intermediate portion of said rudder and journaled in the housing.

In testimony whereof I affix my signature, in the presence of two witnesses.

LOUIS ZWIESLER.
